UNITED STATES PATENT OFFICE.

HENRY K. PORTER, OF BOSTON, MASSACHUSETTS.

DESIGN FOR AN AXLE-YOKE.

SPECIFICATION forming part of Design No. 14,971, dated April 22, 1884.

Application filed July 21, 1883. Term of patent 14 years.

To all whom it may concern:

Be it known that I, HENRY K. PORTER, of Boston, in the county of Suffolk and State of Massachusetts, have invented a new and original Design for Axle-Yokes, also known as "clip-yokes," "clip-bars," and "axle-clip ties," which will, in connection with the accompanying drawings, be hereinafter fully described, and specifically defined in the appended claims.

This invention relates to a design for the article of carriage-hardware known to the trade as "axle-yokes" or "clip-yokes," and it consists in the peculiar configuration of the ends 15 of the yoke, as shown in the accompanying illustrations, in which—

Figure 1 is a perspective view; Fig. 2 a top or plan view, and Fig. 3 a side elevation, of an axle-yoke embodying my design, these several 20 views being deemed necessary to fully illustrate my design.

The leading feature of my invention consists in an axle-yoke having the side planes thereof bounded at each end by a line, which constitutes a compound curve termed an "ogee," the top plane being bounded at each end by a line, constituting a double ogee, the convex lines whereof meet at the longitudinal center of such plane, and the end planes of the yoke 25 being bounded at their upper line by an arc of a circle or single curve.

In said figures, *a* is the upper side or plane of the yoke, that portion thereof which is included between lines *B* representing the portion 30 thereof which is occupied by the axle, while that portion of the yoke included be-

tween each line *B* and the nearest end or plane *g* constitutes the finished portion, the same being so formed that lines *d* in each half of their length, as subdivided by line *A*, constitute a 40 compound curve or ogee, while lines *e*, which bound the planes *b*, are also compound curves or ogees, the end plane *g* at its upper limit being shown as bounded by an arc, *f*, which terminates in common with the lower ends of 45 lines *e* at the lower corners of the yoke, whose lower plane is a parallelogram.

I claim—

1. The design for axle-yokes herein shown and described, the same consisting in the configuration of the respective ends, whereby the side planes *b* are at each end bounded by a line constituting an ogee, and the top plane, *a*, is bounded at each end by a line constituting a double ogee, whose convex lines meet at 55 the longitudinal center of said plane.

2. The design for axle-yokes herein shown and described, the same consisting in the configuration of the respective ends, whereby the side planes, *b*, are at each of their ends bounded by a line constituting an ogee, and the top plane is bounded at each end by a double ogee, whose convex lines meet at the longitudinal center of said plane, and the end planes are bounded at their upper edge by an arc or curve, whose ends terminate at the lower corners of the yoke.

HENRY K. PORTER.
